UNITED STATES PATENT OFFICE.

HOWARD RAY TUTTLE, OF BLISSFIELD, MICHIGAN.

STONE CATCHER FOR BEET SLICERS.

Application filed June 23, 1926. Serial No. 118,109.

An object of my invention is to provide an improved stone catcher for beet slicers of the drum type commonly known as Maguin slicers, of which there are many in use in the United States. My invention is characterized by the fact that my rock catcher can be easily and quickly thrown into operating position when a rock is discovered in the slicer, and also that when same is in its operating position the beets, rock, etc. will pass in a continuous stream from inside the slicer into my rock catcher and automatically out through the end of same, which results in an action that is much more effective in removing the rock or other hard foreign substance from the slicer, than can be obtained with the rock catchers ordinarily furnished on these slicers.

It is understood that the presence of rocks or other hard foreign substances such as iron, nuts, bolts, etc. in the slicer is very objectionable, as same destroys or greatly impairs the knives which revolve in the slicer to cut the beets which are continuously fed into same.

The rock catcher ordinarily used on slicers of the above make consists of a cylinder passing into the slicer, the outer end of said cylinder being closed and having a small handle the length of which approximately equals the diameter of the cylinder, for the purpose of turning the cylinder on its seat when a rock is discovered in the slicer. At an appropriate place in the cylindrical wall of said rock catcher, a rectangular opening is formed therein, for permitting the beets, stone, etc. to enter this rock catcher when same is thrown or rotated into operating position. Ordinarily, when there is no stone in the slicer, this cylinder is revolved into its normal position where the above mentioned cylindrical opening is blanked off by the surrounding housing in such manner that no beets or other substance can enter the rock catcher which is thus kept empty to provide a small amount of space into which the beets can rush, and presumably carry the stone, when the rock catcher is thrown into operation. The trouble with these ordinary rock catchers is that owing to the corrosion caused by the beet juices which saturate all parts of the slicer during operation, these ordinary rock catchers, owing to their excessive bearing surface, can only be turned with great difficulty which takes altogether too much

time in effecting same, and the rock often does its damage before these ordinary rock catchers can be turned into operating position. Still more important than this however, is their imperfect operation after they are thrown into position. Since they can only receive from the slicer a comparatively few beets before the space in same is entirely filled, after which no more beets can pass from the slicer, it naturally follows that frequently the rock which it is desired to remove is not located amongst the few beets that rush into the rock catcher and plug same up to capacity, with the result that the rock is still in and cannot be removed from the slicer at all, and then considerable damage to the knives and other parts of the machine results. Furthermore, since it is necessary finally to pull this rock catcher out of the slicer in order to empty from it the beets and the rock which was hoped would enter same, much difficulty and delay in this respect is often encountered because many of the beets will be part way in and part way out of this cylindrical rock catcher, and by locking or jamming themselves crosswise of other fixed parts of the surrounding slicer housing, practically bind or lock the rock catcher in the slicer, making it very difficult to remove the rock catcher for emptying same. The delays often experienced on this account are exceedingly annoying.

All the objections previously mentioned, are eliminated by my improved stone catcher. I reduce the bearing area of same to narrow widths, which makes it exceedingly easy to rotate the rock catcher into operating position in spite of the normal corrosion at the points of bearing contact. This easy rotation is further facilitated by means of the adequate turning lever which I furnish for this purpose. Furthermore, by opening the end of my rock catcher which projects out through the side of the slicer, in place of sealing up this end by a closure like in the common rock catchers, the beets flow in the continuous stream from the inside of the slicer through my cylindrical rock catcher and out through the open end of same, until the offending rock, bolt or other matter, comes out of the slicer. At least the operator can reach into my rock catcher through the open end of same with his hand, or can poke into same with a rod, for the purpose of keeping the beets continuously coming

through and out of the open end of same until the rock comes out. Obviously this is much more practicable than the old type of rock catchers ordinarily furnished on these 5 slicers.

Other objects, advantages and features of invention may appear from the accompanying drawings, the subjoined detailed description and the appended claims.

10 The accompanying drawings illustrate the invention.

Fig. 1 is a transverse section through a beet slicer equipped with my improved stone catcher. In this figure the stone catcher is 15 shown in its normal inoperative position corresponding to the time when there is no stone in the slicer to be removed.

Fig. 2 is a similar view showing the stone catcher only, but in its operative position 20 for removing the beets, stone, etc. from the slicer.

Fig. 3 is a transverse section in plan through a slicer equipped with my improved rock catcher.

25 Fig. 4 is a side view of the slicer showing my rock catcher in place.

Fig. 5 shows the principal member comprising my rock catcher, removed from the slicer.

30 The general parts of the slicer are well known, and consist of a rotary drum carried on a horizontal shaft 1, and on the inner face of this rotary drum are carried a continuous series of beet cutting knives 2 of well known type. The beets are fed 35 through a hopper 3, see Fig. 4, into the slicer where they quickly move into the position shown in Fig. 1, the spirally shaped pressure plate 4 serving to wedge or press the 40 beets downward upon the knives to effectively cut same. Toward the end of this pressure plate there is a cylindrical housing 5 for carrying the cylindrical part 6 of the stone catcher, and just beyond this stone 45 catcher is fastened the counterplate 7 which normally prevents the beets from being completely carried around the slicer as indicated in Fig. 1, and which also serves to deflect the beets, stone, etc., into the stone 50 catcher when the latter is revolved into its operating position as indicated in Fig. 2.

As best indicated in Figs. 3 and 5, this stone catcher consists principally of a cylindrical member 6, having a more or less rectangularly shaped opening 8 therein, and also having relatively narrow bearing bands 55 9 on the outer surface thereof, a long hand lever 10 being also attached thereto. As indicated in Fig. 3 the cylindrical member 6 projects through and beyond the stationary non-rotating side member 11 of the slicer. Suitable cleats or straps 12 are fastened to 60 this side member 11, and cooperate in permanently holding the rock catcher 6 in its housing 5, i. e. they prevent the rock catcher

from coming out of the slicer by endwise motion. This is accomplished by having these cleats butt against the side of the outermost bearing band 9, functioning in this respect more or less like a thrust bearing. Even though the cylindrical stone catcher 70 cannot come out of the housing endwise, it is obvious that same can be rotated therein by means of the hand lever 9. In order to permit freer rotation of the stone catcher, and to make possible the cutting of beets by same if necessary, I prefer to bevel the edges 13 of same, adjacent the opening 8, as best seen in Figs. 1, 2 and 5. Also to prevent muck and fine cuttings from leaking 75 into the clearance space between housing 5 and cylinder 6, I prefer to roll out the bevelled edges 13 of the cylinder as shown in Figs. 1, 2 and 5. A simple quick-opening 80 latch or member 15 preferably is also provided. This member furnishes a stop or rest on which the hand lever 10 can normally rest in its horizontal position, to prevent the rock catcher accidentally turning from its 85 normally closed to its open operating position. In Fig. 3 the dotted position of hand lever 10 is shown resting on this latch 15, the position being dotted in as it does not correspond with the open position shown by the balance of the rock catcher in this view. 90 The approximate relation between the hand lever 10 and the opening 8 in the rock catcher is best shown in Fig. 5. Fig. 4, shows in full line the actual position of hand lever 10 corresponding to the normal closed position of the rock catcher. It is seen to be resting on the latch 15. The dotted position of hand lever 10 in Fig. 4 shows same swung around to its position when the rock catcher 95 is in open operating position. To swing this hand lever 10 from its horizontal closed position, down into its open position, it is merely necessary to rotate latch 15 out of the way horizontally around its pin 16, see 100 Figs. 3 and 4, which can be very quickly 105 done, and it is then practically no effort whatever to force the hand lever 10 down into its dotted position shown in Fig. 4 for the purpose of quickly throwing the rock catcher 110 into open position. When this is done the beets, rock, etc. will obviously pass from inside the slicer, through opening 8 into the cylindrical rock catcher, and in view of the operating pressure these beets, etc. will automatically push themselves out of the open end 17 of the rock catcher in a continuous stream onto the floor, until the rock 115 is discharged, after which the hand lever 10 can again be swung up into its horizontal position to close the rock catcher. Thereafter the operation of the slicer continues as usual, the rock or other hard foreign substance 120 having been safely removed from same.

Owing to the comparatively narrow width 130

of my bearing bands 9, there is obviously no considerable bearing resistance against the rotation of my rock catcher.

Various modifications and adaptations of my improved rock catcher can of course be made in accordance with the tastes and desires of the designer for user thereof without departing from the spirit of my invention.

It is another important advantage of my rock catcher that same operates to remove and catch the rock from the slicer, without stopping the slicer or in any way retarding or interfering with the continued slicing operation of the machine. This is not possible with the ordinary rock catchers furnished in this kind of a slicer. With those ordinary rock catchers the slicer must invariably be stopped before the rock catcher can be emptied of its beets, rock, and other trash, for the purpose of being sure that the rock has been removed from the slicer. Since delays of this character at the slicing machines, retard and delay the entire sugar factory, these delays at the slicer are carefully guarded against by the management of the sugar factories. Therefore in so far as my rock catcher wholly eliminates the delays just mentioned, its use is of great advantage.

I claim:

1. In a beet slicer having a stationary side member, a cylindrical drum revolving about a horizontal axis and having cutting knives fastened on the internal cylindrical face of same, and a stationary housing within said cylindrical drum, a cylindrical rock catcher rotatably mounted in said housing and projecting through said stationary side member, said cylindrical rock catcher having a hand lever for turning same and having the

end which passes through said stationary side member open, said cylindrical rock catcher also having an opening in the cylindrical face of same arranged to afford a continuous passage from the inside of the slicer through the last said opening and out through the open end of said cylindrical rock catcher to the space outside of said slicer.

2. In a beet slicer having a stationary side member, a cylindrical drum revolving about a horizontal axis and having cutting knives fastened on the internal cylindrical face of same, and a stationary housing within said cylindrical drum, a cylindrical rock catcher rotatably mounted in said housing, and narrow bearings between said cylindrical rock catcher and said housing for permitting the easy rotation of said rock catcher within said housing.

3. In a beet slicer a stationary side member having a hole therethrough, a drum adapted to revolve around a horizontal axis, a stationary housing within said drum, a cylindrical rock catcher rotatably mounted in said housing and having one of its ends normally open and located adjacent said hole through the stationary side member, said rock catcher also having an opening through its cylindrical face arranged to afford a continuous passage from the inside of said slicer through the last said opening and out through said open end of the rock catcher and through said hole in the stationary side member to the space outside said slicer.

In testimony whereof I have hereunto set my hand at Blissfield, in the county of Lenawee, Michigan, this 12th of December, 1925.

HOWARD RAY TUTTLE.
